UNITED STATES PATENT OFFICE.

HARVE R. STUART, OF SPRINGFIELD, OHIO, ASSIGNOR TO THE ROBBINS & MYERS COMPANY, OF SPRINGFIELD, OHIO, A CORPORATION OF OHIO.

OSCILLATING FAN.

Application filed February 10, 1926. Serial No. 87,402.

This invention relates to improvements in oscillating fans for ventilating purposes, it more particularly relating to means for disconnecting the fan from the oscillating devices and holding the fan stationary so far as oscillatory movement is concerned.

The invention has to do with that type of oscillatory fan in which the motor and fan are mounted for swivelling movement and the devices which oscillate the fan are operated from the motor shaft.

The object of the invention is to provide simple and effective means for disconnecting the oscillating devices by an arrangement whereby the devices may be disconnected or again connected while the fan is in motion and also to provide an arrangement whereby the fan may be held rigidly in stationary position so far as swivelling is concerned without the necessity of providing set screws or other positive holding devices of that character.

In the accompanying drawings:

Fig. 1 is an elevation of an oscillating fan embodying the improvements.

Fig. 2 is a section on the line 2-2 of Fig. 1.

Fig. 3 is a section on the line 3-3 of Fig. 2.

Fig. 4 is a section on the line 4-4 of Fig. 2.

Fig. 5 is a perspective view of the clutch.

Fig. 6 is a rear elevation of the parts shown in Fig. 1 with the casing sectioned.

Referring to the drawings, 1 represents a supporting standard to which is pivotally connected a head 2, the connection being made through a bolt 3 having a thumb nut 4 in the usual way to permit the head and fan carried thereby to be tilted. The motor 5 has a trunnion 6 which is swivelled in the head 2 and on the forward end of the motor shaft 6' is mounted the hub 7 of a fan of usual form. The rear end of the motor shaft 6' has a worm 7 which drives the worm wheel 8, the worm wheel 8 being loosely mounted upon a shaft 9, the lower enlarged end of which is journaled in the support 10 which is integrally connected with and carried by bracket arms supported from the motor frame. These bracket arms have a bearing for the rear end of the motor shaft and also have an upwardly projecting sup-

port 12 to the upper end of which is secured an angle plate 13.

Fixed to a reduced portion of the shaft 9 is a collar 14 having a flange 15. This flange 15 has a notch 15' and the hub of the gear 8 is provided with a pair of notches 8'. Loosely mounted on the upper reduced portion of the shaft 9 is a disk 17 having a tooth 17' and also having attached thereto a yoke 19, the upper end of which has in turn connected therewith a pin 20 having a knurled finger piece 21. The pin 20 projects through an opening in the guide plate 13 and also through an opening in the casing 22 with the knurled finger piece 21 on the outside of the casing. A coil spring 18 is interposed between the disk 17 and a pin in the upper end of the shaft 9.

The lower end of the shaft 9 has attached thereto a crank arm 23 provided with an eccentric pin 24 upon which is loosely mounted a pinion 25. The support 10 has downturned side flanges 10' to which is secured by screws 26 a U-shaped supporting piece 27. Between the flanges of the piece 27 and the flanges 10' is clamped a stationary internal gear 28 concentric with the shaft 9. Mounted in the supporting piece 27 is a shaft 29 the upper end of which has formed therewith an annular cup-shaped member 30 which carries an internal gear 32 concentric with the stationary internal gear 28. The gear 32 has a greater number of teeth than the gear 28, in the present arrangement the gear 28 being provided with sixteen teeth and the gear 32 with seventeen teeth. The pinion overlaps these gears and is in mesh therewith. The lower end of the shaft 9 has a crank arm 33 which is connected by a link 34 with a pin 35 which extends through an opening in a lug 36 projecting from the head 2.

In operation, if it is desired to oscillate the fan the tooth 17' is caused to engage the notch 15' in the disk 15 and one of the notches 8' in the worm wheel 8 so that rotary movement of the wheel 8 will be imparted to the shaft 9. As the pinion 25 moves about the teeth of the gears 28 and 32, the gear 32 will be slowly rotated in a well known way, the degree of rotation in the particular arrangement shown being a distance of one tooth of the gear 32 to one

rotation of the crank 24. If now it is desired to hold the fan stationary by grasping the knurled finger piece 24 and lifting the disk 17 to withdraw the tooth 17' from engagement with the worm wheel 8 rotation of the shaft 9 is stopped and by giving the disk 17 a slight turn relatively to the disk 15 the tooth 17' may be brought to rest upon the disk 15 and thus hold the parts disengaged. 5 When thus disengaged the motor and fan will be locked in their stationary position so far as oscillation is concerned by the speed reducing gearing because any oscillatory movement of the parts would have the effect of rotating the gear 32 which is locked from rotation by the stationary gear 28 through the medium of the pinion 25.

To again disengage the parts it is necessary only to give the disk 17 a slight turn 20 to bring its tooth 17' in registry with the notch 15', after which the engagement of the tooth with one of the notches 8' will be automatic.

Having thus described my invention I 25 claim:

1. In an oscillating mechanism for a motor and fan mounted to oscillate, the combination of a motor shaft, a driven shaft having a crank pin, a pinion mounted upon said pin, a stationary internal gear and a rotatable internal gear concentric with said driven shaft and in mesh with said pinion, said gears and pinions constituting speed reducing mechanism, manual means for connecting and disconnecting said driven shaft with and from said motor shaft, a crank connected with said rotatable gear, and a link pivotally connecting said crank with a stationary part, said motor and fan being locked against

movement by said speed reducing gearing 40 excepting when said gearing is connected with said motor shaft.

2. In an oscillating mechanism, a motor and fan mounted to oscillate, a driven shaft operatively connected with said motor, a revoluble pinion eccentrically connected with said shaft, a stationary gear and a rotatable gear concentric with said shaft and in mesh with said pinion, said gear and pinion constituting speed reducing mechanism, manual means for connecting and disconnecting said driven shaft with and from said motor shaft, a crank connected with said rotatable gear, and a pivotal connection between said crank and a stationary part, said motor and fan being locked against movement by said speed reducing gearing excepting when said gearing is connected with said motor shaft. 45

3. In an oscillating mechanism, a motor and fan mounted to oscillate, a driven shaft operatively connected with said motor, a rotatable pinion eccentrically mounted at an end of said driven shaft, a stationary internal gear and a rotatable internal gear meshed with said pinion, said gears having different numbers of teeth, manual means for connecting and disconnecting said driven shaft with and from said motor shaft, a crank connected with said rotatable gear, and a pivotal connection between said crank and a stationary part, said motor being locked against movement by said gearing excepting when said gearing is connected with said motor shaft. 50

In testimony whereof, I have hereunto 55 set my hand this 5th day of February, 1926.

HARVE R. STUART.
